UNITED STATES PATENT OFFICE.

ROBERT D. BENNETT, OF MANCHESTER, ENGLAND, ASSIGNOR TO MARCIUS BIBBERO, OF SAME PLACE.

WASHING-MACHINE.

SPECIFICATION forming part of Letters Patent No. 247,877, dated October 4, 1881.

Application filed May 13, 1881. (No model.) Patented in England July 26, 1879.

To all whom it may concern:

Be it known that I, ROBERT DOUGLAS BENNETT, of Manchester, England, have invented certain useful Improvements in Washing-Machines, of which the following is a specification.

The object of my invention is to provide a washing-machine whose construction shall be such as to allow the introduction and removal of the articles operated upon without removing the rubber from the tub.

My invention consists in hinging one end of the rubber to radial arms extending from the shaft, and providing the other end with hinged bolts engaging in slots in other radial arms, whereby the said rubber may be lifted from one end for the introduction and removal of articles and then secured in place, as will be hereinafter more fully explained.

In the accompanying drawings, forming part of this specification, Figure 1 is a side elevation, partially in section, of my improved machine; and Fig. 2 is a plan view.

Similar letters of reference indicate corresponding parts.

A is a box or receptacle, which may be of any suitable construction and mounted on legs, if desired. Within the box A is the yielding bed, consisting of a curved grating, b, which, as shown, is composed of rounded bars of wood, attached by each end to wooden side cheeks, c c. To the said cheeks are attached two hollow metal floats, d d, which are made of thin copper or zinc or other suitable metal. The floats add to the buoyancy of the grating b, so that when a quantity of water is placed in the receptacle, the said grating offers a resistance to being submerged. In case the said grating be not buoyant without the aid of the floats, the floats are proportioned to impart a suitable buoyancy to the grating. The yielding bed so formed is free to rise and fall within the receptacle, being guided by the sides or other suitable means.

To the sides of the box A standards e e are secured by bolts passing through slots in the standards, so that the standards may be adjusted vertically, and in the upper ends of these standards bearings are formed for a rocking shaft, f. On this rocking shaft are fixed arms

g g, and to these arms is hinged a curved frame, h, to which are fixed bars i i, of wood or other suitable material, which constitute the vibrating rubber. The curve formed by these bars is struck from the axis of shaft f and frame h, or thereabout. The curve of the yielding bed is preferably struck with a radius which is a little shorter than that of the vibrating rubber; but I do not limit myself in that particular. The frame h is hinged at k to the arms g, and can be turned up into the position indicated by the dotted lines, in order that the articles to be washed or treated may be introduced below the bars i. When this is effected the said frame is turned down into the position indicated by the full lines, and is secured in that position by means of hinged bolts l l'. These bolts are hinged to the frame h, and are formed with projections which enter holes in arms g.

On one end of the shaft f is fixed an arm, m, to which one end of a connecting-link is jointed. The other end of this link engages with a crank-pin, o, which is fixed in a disk that is upon a shaft, p. This shaft is fitted to revolve in suitable bearings which are secured to the receptacle, and upon the other end of the shaft is fixed a spur-pinion, s, which gears with a spur-wheel, r, which is mounted upon a fixed stud.

To the spur-wheel is fixed a suitable fly-wheel or hand-wheel, t.

It will be seen that when the hand-wheel is turned a vibrating motion will be communicated to the arms g and the rubber-frame h.

When the machine is to be used for washing, water and detergent are put in the receptacle and the articles placed below the rubber-frame h, in the manner before indicated. The hand-wheel t is then turned, whereby the rubber is caused to vibrate and to operate upon the articles, the buoyancy of the bed or grating b furnishing a yielding upward pressure of the articles against the rubber.

Washing-machines constructed in accordance with my invention may be used in all the processes of washing, cleansing, rinsing, and starching.

Having thus fully described my invention,

I claim as new and desire to secure by Letters Patent—

The combination, with the shaft *f* and arms *g*, of the rubber-frame *h*, hinged thereto, and 5 provided with bolts *l* *l'*, substantially as described, whereby one end of said rubber may be lifted for the purpose of introducing or removing articles, and then returned to and locked in its normal position, as set forth.

The above specification of my invention is signed by me this 20th day of April, 1881.

ROBERT DOUGLAS BENNETT.
